UNITED STATES PATENT OFFICE.

CYRIL CLARKE BOVILLE MORRIS, OF LONDON, ENGLAND.

CARBURETER.

1,079,947.

Specification of Letters Patent.

Patented Dec. 2, 1913.

Application filed February 5, 1913. Serial No. 746,332.

To all whom it may concern:

Be it known that I, CYRIL CLARKE BOVILLE MORRIS, of Ridgmount Gardens, Chenies street, London, England, engineer, have invented certain new and useful Improvements in and Relating to Carbureters for Internal-Combustion Engines, of which the following is a specification.

This invention relates to carbureters for internal combustion engines of the type in which a floating valve, that is to say, a valve held on its seat by its own weight, in the mixture stream controls the fuel supply by a taper needle or like valve, and especially to carbureters for use with fuel heavier than petrol, and has for its object to provide an improved carbureter and arrangement of parts.

This invention consists in a carbureter of the kind referred to, and having a main air supply and an auxiliary air supply in which the formation of the initial mixture, and the addition to it of auxiliary air, are effected before passage through the floating valve.

This invention also consists in the improvements in and relating to carbureters hereinafter indicated.

The drawings filed herewith show one form of carbureter according to this invention:

Figure 1 is a sectional front elevation; Fig. 2 is a side elevation; Fig. 3 is an end elevation; and Fig. 4 is a detail of a second form of carbureter according to this invention.

a is a casing provided with a valve seat *b*, *c* is the main air inlet and air passage, *d* is the outlet for the carbureted air to a heating device which may be of any suitable pattern as for instance, a coil *z* in the exhaust manifold of the engine; *e* is the inlet for the heated carbureted air to mixing chamber *f*; *g* are auxiliary air inlets; *h* the controlling valve for auxiliary air; *j* is a weighted valve adapted to rest on the seat *b*; and having a stem *k* working in a guide *m*; *n* is a tapered pin attached to the stem *k* and working through an orifice *o* in the cap *p*; *q* is a plunger working in a cylinder *r*, and forming a fuel reservoir and a dashpot; *s* is the inlet for liquid fuel supplied at say two to four pounds per sq. inch pressure when using heavy oil.

The dashpot works in the supply of fuel under pressure. The fuel can easily pass through ports in the plunger, so that the

position or movement of the plunger cannot affect the flow of fuel to the jet or spray to any appreciable extent.

The controlling valve *h* for the auxiliary air supply is connected by a link *t* to an arm *t'* for actuating the throttle valve *v*. *w* is the induction pipe.

In operation, liquid fuel is forced through the inlet *s* under pressure independently of the suction of the engine to the dashpot cylinder *r*, the pressure being preferably under the control of the driver, and passes out through the orifice *o* in a fine spray at right angles to the main air supply, and is taken up by the air. The carbureted air then enters the heating device, and subsequently enters the mixing chamber *f*, passes round the floating valve *j*, and passes to the engine by the induction pipe *w*. The lift of the valve by raising the pin *n* controls the annular aperture *o*, through which the liquid fuel passes, and therefore controls the fuel supply.

The main air supply when the throttle is fully opened, amounting say to 20 per cent. to 25 per cent. of the air required, passes the orifice of the jet or spray at right angles at a high velocity, insuring relatively complete atomization of the fuel.

The casing *a* is provided with a cylindrical extension *2*, in which rides a balancing piston *3* open to atmospheric pressure on the upper side and to the suction of the engine on the other side. This cylinder and piston could be used as a dashpot if desired in place of the dashpot *q* *r*. Should the dashpot be placed at the upper end, then the tapered pin *n* may work into a chamber 4 as shown in Fig. 4. It will be observed that in the form shown in Fig. 1 the fuel passes necessarily through perforations 5 in the dashpot, and it is important that the total cross sectional area of the ports or the amount of the leak around the piston shall 100 exceed the maximum jet area to avoid starving the same.

The lifting valve *j* is in the form of a sleeve, and is provided with ports 7 which are wider at their upper ends than at their lower ends. The ports are so proportioned that on any rise of the valve and consequent enlargement of the fuel inlet, the passages through the valve are opened proportionately to the increase in fuel supply, and constancy of mixture is better maintained. This valve acts as a damper and with its

use it is possible to dispense with the dash-pot when used with certain types of engines.

The auxiliary air supply *g* is or may be regulated with the throttle lever. A valve 5 may be provided to close the supply of liquid fuel when desired.

The air supply may be sub-divided so that one part is constant, one part adapted to be regulated independently and one part adapted to be directly connected up to the throttle. The last named may be so connected to the throttle that it only admits air after the throttle has been opened a predetermined amount, say two-thirds open. The constant air supply is shown at 8 in the drawings.

In carburetors constructed and operating as described, the lift of the mixture valve is determined by the flow of air through or past it, no matter whether the air is drawn through the main air inlet only, or through the main and auxiliary inlets, and therefore the mixture strength remains relatively constant, irrespective of the position of the auxiliary air inlet valve. It will therefore be seen that in a carburetor made in accordance with this invention, the strength of the mixture can be maintained constant whatever may be the position of the throttle or 30 the additional air supply valve. Thus, when the demand of the engine is such that the necessary amount of gas cannot be drawn through the main air inlet, the auxiliary air valve is opened by hand or otherwise, and the additional amount of gas flowing through the valve increases its lift, and in consequence, the fuel inlet is enlarged, but although as a result the air entering by the main inlet becomes too highly 40 carbureted to form a good explosive mixture, the richness of the mixture is corrected in the chamber below the lifting valve by the additional auxiliary air.

The pressure of the fuel is or may be under the control of the driver, so that consistent results may be obtained with fuel of different viscosity or volatility or under different atmospheric conditions by altering the pressure. No float chamber is therefore 50 required.

In a carburetor as described above, the parts are so disposed that acceleration always takes place on a weak mixture, with the result that no smoke is emitted from the exhaust when working on heavy fuel, as is likely to occur when accelerating on a strong mixture.

The vaporizer being disposed between the jet or spray and the chamber below the lifting valve, there is an immediate weakening of the mixture in the chamber on opening the throttle, and auxiliary air supply valve, and the weak mixture is continued to be supplied until the column of carbureted air 65 in the vaporizer at the time of opening the

throttle has been consumed and replaced by the richer charge consequent on the additional lift of the air valve and pin due to the opening of the auxiliary air valve.

In the form above described the fuel supply has been indicated as controlled by a needle valve, but it will be understood that a hollow sleeve or other suitable device may readily be substituted therefor. In some cases forced induction may be employed.

What I claim and desire to secure by Letters Patent is:

1. A carburetor comprising the combination of a casing, a valve seat in the casing, a floating valve disposed above the valve seat 80 a mixing chamber below the valve seat, a tapered pin attached to valve and extending downward, a fuel reservoir disposed below the mixing chamber, said reservoir having an orifice disposed axially of the valve and into which the tapered pin passes, an air inlet and passage disposed between the mixing chamber and the fuel reservoir said passage traversing the pin attached to the valve at right angles, a carbureted air inlet to the mixing chamber and means for heating the air on its way to the mixing chamber, and means for supplying fuel to the fuel chamber under pressure.

2. A carburetor comprising the combination of a casing, a valve seat in the casing, a cylindrical extension to the casing above the seat, a floating valve disposed between the valve seat and cylindrical extension, a piston on said valve working in the cylindrical extension, a mixing chamber below the valve seat, a tapered pin attached to valve and extending downward, a fuel reservoir disposed below the mixing chamber, said reservoir having an orifice disposed axially of the valve and into which the tapered pin passes, an air inlet and passage disposed between the mixing chamber and the fuel reservoir, said passage traversing the pin attached to the valve at right angles, a carbureted air inlet to the mixing chamber and means for heating the air between on its way to the mixing chamber, and means for supplying fuel to the fuel chamber under pressure.

3. A carburetor comprising the combination of a casing, a valve seat in the casing, a cylindrical extension to the casing above the seat, a floating valve disposed in the casing between the valve seat and cylindrical extension, a piston on said valve and working in the cylindrical extension, a guide in the casing below the valve seat and disposed axially of the valve, a stem to the valve working in the guide, a mixing chamber below the valve seat, a tapered pin attached to valve and extending downward, a fuel reservoir disposed below the mixing chamber, said reservoir having an orifice disposed axially of the valve and into which

the tapered pin passes, an air inlet and passage disposed between the mixing chamber and the fuel reservoir said passage traversing the pin attached to the valve at right angles, a carbureted air inlet to the mixing chamber, and means for heating the air between on its way to the mixing chamber, and means for supplying fuel to the fuel chamber under pressure.

10 4. A carbureter comprising the combination of a casing, a valve seat in the casing, a floating valve disposed above the valve seat, a mixing chamber below the valve seat, a tapered pin attached to valve and extending downward, a fuel reservoir disposed below the mixing chamber, said reservoir having an orifice disposed axially of the valve and into which the tapered pin passes, an air inlet and passage disposed between the mixing chamber and the fuel reservoir said passage traversing the pin attached to the valve at right angles, a carbureted air inlet to the mixing chamber and means for heating the air between on its way to the mixing chamber, means for admitting a constant air supply and a valve on the mixing chamber for controlling a further supply of auxiliary air to the mixing chamber and means for supplying fuel to the fuel chamber under pressure.

30 5. A carbureter comprising the combination of a casing, a valve seat in the casing, a cylindrical extension to the casing above the seat, a floating valve disposed in the casing between the valve seat and cylindrical extension, a piston on said valve working in the cylindrical extension, and open to atmosphere pressure on its upper side a guide in the casing below the valve seat and disposed axially of the valve, a stem to the valve working in the guide, a mixing chamber below the valve seat, a tapered pin attached to valve and extending downward, a fuel reservoir disposed below the mixing chamber, said reservoir having an orifice disposed axially of the valve and into which the tapered pin passes, an air inlet and passage disposed between the mixing chamber and the fuel reservoir said passage traversing the pin attached to the valve at right angles, a carbureted air inlet to the mixing chamber, and means for heating the air between on its way to the mixing chamber, a valve on the mixing chamber for controlling the supply of auxiliary air to the mixing chamber and means for supplying fuel to the fuel chamber under pressure.

6. A carbureter comprising the combination of a casing, a valve seat in the casing, a floating valve disposed above the valve seat, a mixing chamber below the valve seat, a tapered pin attached to valve and extending downward, a fuel reservoir disposed below the mixing chamber, said reservoir having

an orifice disposed axially of the valve and into which the tapered pin passes, a piston on said pin working in said reservoir and forming a dashpot, an air inlet and passage disposed between the mixing chamber and the fuel reservoir said passage traversing the pin attached to the valve at right angles, a carbureted air inlet to the mixing chamber and means for heating the air between on its way to the mixing chamber, and means for supplying fuel to the fuel chamber under pressure.

7. A carbureter comprising the combination of a casing, a valve seat in the casing, a cylindrical extension to the casing above the seat, a floating valve disposed between the valve seat and cylindrical extension, a piston on said valve working in the cylindrical extension, a mixing chamber below the valve seat, a tapered pin attached to valve and extending downward, a fuel reservoir disposed below the mixing chamber, said reservoir having an orifice disposed axially of the valve and into which the tapered pin passes, a piston on said pin working in said reservoir and forming a dashpot, an air inlet and passage disposed between the mixing chamber and the fuel reservoir, said passage traversing the pin attached to the valve at right angles, a carbureted air inlet to the mixing chamber and means for heating the air between on its way to the mixing chamber, and means for supplying fuel to the fuel chamber under pressure.

8. A carbureter comprising the combination of a casing, a valve seat in the casing, a floating valve disposed above the valve seat, the floating valve being provided with ports of varying width through which the mixture passes so that the port area open for the passage of the mixture is more or less proportioned to the opening of the fuel supply device, a mixing chamber below the valve seat, a tapered pin attached to valve and extending downward, a fuel reservoir disposed below the mixing chamber, said reservoir having an orifice disposed axially of the valve and into which the tapered pin passes, an air inlet and passage disposed between the mixing chamber and the fuel reservoir said passage traversing the pin attached to the valve at right angles, a carbureted air inlet to the mixing chamber and means for heating the air between on its way to the mixing chamber, and means for supplying fuel to the fuel chamber under pressure.

9. A carbureter comprising the combination of a casing, a valve seat in the casing, a cylindrical extension to the casing above the seat, a floating valve disposed in the casing between the valve seat and cylindrical extension, the floating valve being provided with ports of varying width through which the mixture passes so that the port area open for

- the passage of the mixture is more or less proportioned to the opening of the fuel supply device, a piston on said valve and working in the cylindrical extension, a guide in the casing below the valve seat and disposed axially of the valve, a stem to the valve working in the guide, a mixing chamber below the valve seat, a tapered pin attached to valve and extending downward, a fuel reservoir disposed below the mixing chamber, said reservoir having an orifice disposed axially of the valve and into which the tapered pin passes, an air inlet and passage disposed between the mixing chamber and the fuel reservoir, said passage traversing the pin attached to the valve at right angles, a carbureted air inlet to the mixing chamber and means for heating the air between on its way to the mixing chamber, means for admitting a constant air supply and a valve on the mixing chamber for controlling a further supply of auxiliary air to the mixing chamber, and means for supplying fuel to the fuel chamber under pressure.
10. A carbureter comprising the combination of a casing, a valve seat in the casing, a cylindrical extension to the casing above the seat, a floating valve disposed between the valve seat and cylindrical extension, the floating valve being provided with ports of varying width through which the mixture passes so that the port area open for the passage of the mixture is more or less proportioned to the opening of the fuel supply device, a piston on said valve working in the cylindrical extension, a mixing chamber below the valve seat, a tapered pin attached to valve and extending downward, a fuel reservoir disposed below the mixing chamber, said reservoir having an orifice disposed axially of the valve and into which the tapered pin passes, a piston on said pin working in said reservoir and forming a dashpot an air inlet and passage disposed between the mixing chamber and the fuel reservoir, said passage traversing the pin attached to the valve at right angles, a carbureted air inlet to the mixing chamber, and means for heating the air between on its way to the mixing chamber, means for admitting a constant air supply and a valve on the mixing chamber for controlling a further supply of auxiliary air to the mixing chamber, and means for supplying fuel to the fuel chamber under pressure.
11. A carbureter comprising the combination of a casing, a valve seat in the casing, a cylindrical extension to the casing above the seat, a floating valve disposed between the valve seat and cylindrical extension, the floating valve being provided with ports of varying width through which the mixture passes so that the port area open for the passage of the mixture is more or less proportioned to the opening of the fuel supply device, a piston on said valve working in the cylindrical extension, a mixing chamber below the valve seat, a tapered pin attached to valve and extending downward, a fuel reservoir disposed below the mixing chamber, said reservoir having an orifice disposed axially of the valve and into which the tapered pin passes, an air inlet and passage disposed between the mixing chamber and the fuel reservoir, said passage traversing the pin attached to the valve at right angles, a carbureted air inlet to the mixing chamber and means for heating the air between on its way to the mixing chamber, means for admitting a constant air supply and a valve on the mixing chamber for controlling a further supply of auxiliary air to the mixing chamber, and means for supplying fuel to the fuel chamber under pressure.
12. A carbureter comprising the combination of a casing, a valve seat in the casing, a cylindrical extension to the casing above the seat, a floating valve disposed in the casing between the valve seat and cylindrical extension, the floating valve being provided with ports of varying width through which the mixture passes so that the port area open for the passage of the mixture is more or less proportioned to the opening of the fuel supply device, a piston on said valve working in the cylindrical extension, a guide in the casing below the valve seat and disposed axially of the valve, a stem to the valve working in the guide, a mixing chamber below the valve seat, a tapered pin attached to valve and extending downward, a fuel reservoir disposed below the mixing chamber, said reservoir having an orifice disposed axially of the valve and into which the tapered pin passes, an air inlet and passage disposed between the mixing chamber and the fuel reservoir, said passage traversing the pin attached to the valve at right angles, a carbureted air inlet to the mixing chamber and means for heating the air between on its way to the mixing chamber, means for admitting a constant air supply and a valve on the mixing chamber for controlling a further supply of auxiliary air to the mixing chamber, and means for supplying fuel to the fuel chamber under pressure.
13. A carbureter comprising the combination of a casing, a valve seat in the casing, a floating valve disposed above the valve seat, the floating valve being provided with ports of varying width through which the mixture passes so that the port area open for the passage of the mixture is more or less proportioned to the opening of the fuel supply device, a mixing chamber below the valve seat, a tapered pin attached to valve and extending downward, a fuel reservoir disposed below the mixing chamber, said reservoir having an orifice disposed axially of the valve and into which the tapered pin passes, an air inlet and passage disposed between the mixing chamber and the fuel

reservoir said passage traversing the pin attached to the valve at right angles, a carbureted air inlet to the mixing chamber and means for heating the air between on its way to the mixing chamber, means for admitting a constant air supply and a valve on the mixing chamber for controlling the supply of auxiliary air to the mixing chamber said valve being connected to the

throttle and means for supplying fuel to the fuel chamber under pressure.

In witness whereof, I have hereunto signed my name in the presence of two subscribing witnesses.
